UNITED STATES PATENT OFFICE.

JOSEPH B. MOWRY, OF MANSFIELD, OHIO.

MEDICINE-DOSE INDICATOR.

SPECIFICATION forming part of Letters Patent No. 623,171, dated April 18, 1899..

Application filed January 21, 1899. Serial No. 702,975. (No model.)

To all whom it may concern:

Be it known that I, JOSEPH B. MOWRY, a citizen of the United States, residing at Mansfield, in the county of Richland and State of Ohio, have invented certain new and useful Improvements in Medicine-Dose Indicators; and I do hereby declare the following to be a full, clear, and exact description of the invention, such as will enable others skilled in the art to which it appertains to make and use the same.

My invention relates to certain improvements in what may be termed "medicine-dose indicators."

It has for its object, as intimated, to provide for readily indicating the interval or time of administering medicine to a patient; also, to guard against the accidental movement or displacement of the indices or hands after having been set.

It consists of such indicator provided with concentric series of perforations or foraminous circles produced in the face of a time-dial and pointers or indices adapted to engage said perforations, while incidentally may be arranged in connection therewith memoranda to denote the interval of time of taking the medicine, all substantially as hereinafter more fully disclosed, and specifically pointed out in the claim.

It will be understood that latitude is allowed herein as to details, as they may be varied or changed without departing from the spirit of my invention and the same yet remain intact and protected.

In the accompanying drawings, illustrating the preferred embodiment of my invention, Figure 1 is a face or front view thereof. Fig. 2 is a sectional view of the same. Fig. 3 is a modification thereof involving principally the duplicating of the dials, &c. Figs. 4 and 5 are views of still another modification, and Fig. 6 shows views of dials with various memoranda thereon.

In carrying out my invention I employ, say, a piece of cardboard or other suitable medium A, adapted to be suspended and hung in place and having printed or produced thereon numerals answering to those on the face of a clock-dial, as shown, also pointers or indices B B', sleeved or slipped at their inner ends upon a hub or eyelet a, centrally secured

to the board or dial A in such manner as to permit them to be moved over said dial. These pointers or indices are peculiarly constructed, one being preferably laterally bent or folded inwardly upon itself to form a tooth or projection b and its extreme end b' adapted to register with the dial-numerals, and the other pointer or index similarly bent or folded to form a tooth or projection b² and its extreme end b³ adapted to register with the minute graduations or marks, the purpose of said teeth being presently disclosed.

The dial or board A is provided or produced with concentric series of perforations or foraminous circles c c', suitably arranged with relation to the dial-numerals and adapted to be engaged by the teeth or projections b b² of the pointers or indices B B', whereby the latter are adapted to be held, it will be seen, as they are adjusted to the required points as relates to said numerals and the minute graduations therebetween, and said pointers or indices thus secured or guarded against accidental movement or displacement, as will be readily appreciated.

Upon the rear side of the board or dial A, on the same eyelet or hub as the pointers or indices B B' are held, is arranged a disk or card D or the like, having printed or produced thereon, say, the following: "1½ hrs.", made visible through a slot or opening c² in the dial. The bearing or object of this data, with the arrangement of pointers in connection with dial, will readily address itself to the understanding, and therefore does not require to be further entered into in detail.

In Figs. 3, 4, and 5 are shown duplicate dials, the lower one disclosing the words "When to be taken" and the upper one the words "Was taken," the object of which is apparent. In Figs. 4 and 5 the dial-board is also shown as propped in position to permit it to "stand" upon a mantel or other support.

In Fig. 6 are shown disks or cards D' D², one having produced on it memoranda indicating hours and fractional parts of an hour and the other disk having on it "When to be taken" and "When taken."

Having thus fully described my invention, what I claim, and desire to secure by Letters Patent, is—

As a new article of manufacture, a medi-

cine-dose indicator, consisting of the time-dial having viewing-openings and concentric series of perforations or apertures therein, a centrally or axially pivoted or movable back portion or disk having required data thereon, and pointers or indices centrally pivoted with relation to the aforesaid parts, and formed with bent-up lateral detents or projections to engage said series of perforations, respectively, and having raised or offset terminals

in alignment with, and at right angles to, said lateral detents or projections, substantially as set forth.

In testimony whereof I affix my signature in presence of two witnesses.

JOSEPH B. MOWRY.
